(57) **CLAIM**

The ornamental design for a gaming machine top box, as shown and described.

DESCRIPTION

FIG. 1 is a right perspective view from the front and above a gaming machine top box showing the new design.

FIG. 2 is a front view of the gaming machine top box shown in FIG. 1.

FIG. 3 is a rear view of the gaming machine top box shown in FIG. 1

FIG. 4 is a right side view of the gaming machine top box shown in FIG. 1.

FIG. 5 is a top view of the gaming machine top box shown in FIG. 1.

FIG. 6 is a bottom view of the gaming machine top box shown in FIG. 1; and,

FIG. 7 is a right perspective view from the front and above the gaming machine top box shown in FIG. 1, as mounted on a gaming machine.

The broken line features in FIGS. 2-4 and 6, and the gaming machine in FIG. 7 depict environment and form no part of the claim.

1 Claim, 6 Drawing Sheets
